UNITED STATES PATENT OFFICE.

JAMES H. NEAL, OF CAMBRIDGE, MASSACHUSETTS.

PORTABLE RADIO RECEIVING APPARATUS.

Application filed March 3, 1925. Serial No. 12,924.

This invention relates to a portable radio receiving apparatus especially adapted for use by persons when lying down and particularly by invalids confined to the bed 5 and unable to assume an upright position. The invention further has for its object to provide a simple and efficient apparatus capable of being produced at such small cost as to enable it to be added to the equipment 10 of hospitals and like places, to be used by invalids and especially invalid children.

To this end, the radio receiving apparatus, which may be a crystal set, is located in a flexible or yielding container capable of 15 being placed under the head of the person using the apparatus.

The container may be a pillow of any convenient or desired size, and the apparatus is arranged within the pillow, so that the ear- 20 phone is located near the surface of the pillow, whereby an ear of the person may be brought in close proximity to the mouth of the earphone.

The casing of the pillow or container may 25 be removed to expose the mouth of the phone or it may be of such material as to cover the phone and yet offer substantially no material resistance to the passage of sound.

The apparatus within the pillow or container may and preferably will be provided 30 with antenna and ground leads or conductors accessible from outside the casing, and said antenna and ground leads may and preferably will be extensible and contractible, so that they may be drawn out of the 35 pillow or flexible container when the apparatus is to be used and so that they may be wound up within the pillow when the apparatus is disconnected from the antenna 40 and ground, which permits the pillow and the receiving set carried thereby to be removed from the bed when the latter is to be made up or if it is desired to use the apparatus in a different room or locality.

45 Provision is also made for tuning the apparatus from outside the pillow or container as will be described.

These and other features of this invention will be pointed out in the claims at the 50 end of this specification.

Fig. 1 is a plan view of a radio receiving apparatus embodying the invention.

Fig. 2, a section on the line 2—2, Fig. 1.

55 Fig. 3, an end elevation looking toward the left in Fig. 1.

Fig. 4, a plan of the tuning portion of the

apparatus shown in Fig. 1, with parts broken away.

Fig. 5, a front elevation of the apparatus shown in Fig. 4.

Fig. 6, a section on the line 6—6, Fig. 4 looking in the direction of the arrow thereon.

Fig. 7, a section on the line 7—7, Fig. 4, showing the crystal detector.

Fig. 8, a detail in section of one of the extensible leads or conductors, and

Fig. 9, a diagram of the apparatus shown in Fig. 1.

In the present instance, one embodiment 70 of the invention is shown, in which a crystal set *a* is located in a flexible or yielding container *b*, herein represented as a pillow comprising a casing 10 of ticking or other suitable material and a filling 12 of hair, felt 75 or other fibrous material commonly used in pillows.

The crystal set *a* may be of any suitable or desired construction, and comprises, as herein shown, a crystal 14, a tuning coil 15, a 80 slider 16 co-operating with the tuning coil and movable with relation thereto by a rotatable screw shaft 17 in a manner well understood.

The parts of the crystal set *a* are preferably assembled within a box or casing 20 provided with a removable cover 21, and said box or casing also contains extensible antenna and ground leads or conductors 22, 23, which have one end extended to the outside 90 of the pillow or container *b* so as to be accessible, and which have their inner ends connected to spring-actuated drums or reels 24 located in a suitable box or casing 25, after the manner of metallic tape measures, 95 and as shown in Fig. 8, wherein the metal conductor or lead is represented as partially unwound from the drum or reel 24 against the action of the spring 26, which latter serves to wind the conductor or lead 100 upon the drum or reel when released by the operator.

The conductors or leads 22, 23 are represented as metal ribbons which are provided at their free ends with terminal members 27, 105 28, which serve as convenient means for connection to the antenna and ground.

The free ends of the leads 22, 23 may be provided with enlargements 30 (see Fig. 1) to act as stops which prevent the free 110 ends of the leads from being carried into the pillow and rendered inaccessible.

The screw shaft 17 may be provided with a ball or handle 31, which is accessible from outside the pillow and by which the shaft 17 may be turned to move the slider 16 over the tuning coil 15.

The tuning unit is connected in circuit with an earphone 35 of ordinary construction, which is located in the pillow or container 6 with the mouth piece thereof located in proximity to the surface of the pillow upon which the head of the patient lies.

The earphone 35 may be associated with the pillow in any convenient manner so as to be movable therewith, and in the present instance, the earphone is represented as located within the pillow and supported by the filling 12 thereof, (see Fig. 2), and has its mouth covered only by the pillow casing 10 and the phone may be maintained 20 in a practically fixed position on the pillow by stitches 37 passed through the pillow from the upper to the lower surfaces thereof, as represented in Figs. 1 and 2. The casing 16 of the pillow or container is provided with 25 an opening at one end, through which the parts may be assembled within the container, and said opening may be closed by a flap 38 provided with fastener members 39, which co-operate with fastener members 40 in the 30 body portion 41 of the casing (see Fig. 3).

The body portion 41 may be provided with slits or openings 42 for the passage of the leads 22, 23, and shaft 17, and the flap 38 may be provided with like slits or openings 35 43, through which the leads 22, 23, and the shaft 17 extend when the flap is closed as represented in Figs. 1 and 2.

The boxes 25 for the extensible and contractible antenna and ground leads 22, 23, 40 may and preferably will be located in the box 20 containing the crystal set, and the antenna lead 22 is connected in circuit with the tuning coil 15 by the metal bar 50 (see Fig. 4), and the ground lead 23 is connected with a metal plate 51 with which the 45 slider 16 contacts, as represented in Fig. 6, so that the circuit from the antenna 52 to the ground 53 represented in Fig. 9, is through the tuning coil 15 to the slider 16, through 50 the plate 51 and the ground lead 23.

The crystal 14 herein shown has co-operating with it fixed contact members 55, 56, the member 55 being connected by the wire 57 with the antenna lead 22, and the contact member 56 being connected with one of the phone wires 58. The other phone wire 59 is connected with the plate 51.

From the above description and by reference to the drawing, it will be observed that 60 the flexible container co-operates with the receiving set to form a portable radio receiving apparatus, which is capable of being moved as a unit from one place to another, and which can be connected with the antenna 65 and ground by merely drawing out the leads

22, 23, and connecting them to the antenna and ground terminals of the circuit. The handle or ball 31 can then be rotated to tune in the apparatus with a broadcasting station, and the apparatus can then be placed on the 70 bed with the mouth of the phone beneath the ear of the invalid or other person occupying the bed.

When the apparatus is not being used, the leads 22, 23, may be readily disconnected 75 from the antenna and ground terminals, whereupon they are wound up on reels or drums by the springs 26 and into the position illustrated in Fig. 1.

The portable apparatus is then capable of 80 being removed from the bed until it is desired to use it again, or it may be carried to another room or locality and again put into use.

It will be observed that the apparatus does 85 not in any way interfere with the making of the bed or attending to the invalid when the apparatus is not being used. Furthermore, while the portable apparatus is particularly adapted for use by invalids, it may 90 also be used by well persons when the latter have retired or are resting on a couch or even when sitting in a chair.

The receiving set is preferably a crystal 95 set, which is so inexpensive as to enable hospitals and like places to be provided with a large number of the portable units at a minimum expense.

Furthermore, the portable unit can be supplied to individual homes of poor families 100 at a minimum expense, and used by the people therein.

The flexible container is herein described 105 as a pillow, but it is not desired to limit the invention to this particular form of flexible container.

One embodiment of the invention is herein shown, but it is not desired to limit the invention to the particular construction 110 shown.

Claims:

1. In a portable radio receiving apparatus, in combination, a pillow for yieldingly supporting the head of a person, a radio receiving apparatus located in said pillow and comprising an earphone having its mouth arranged toward the surface of the pillow to which the ear of a person is applied, a tuning coil and a crystal detector within the pillow connected in circuit with said earphone, extensible and contractible antenna and ground leads normally located in said pillow and connected in circuit with said earphone, tuning coil and crystal detector and accessible from outside the pillow to be capable of being withdrawn therefrom for connection with the antenna and ground, and means within the pillow for automatically returning said leads within the pillow when disconnected from said antenna and ground. 125

2. In a portable radio receiving apparatus, in combination, a pillow for yieldingly supporting the head of a person, an earphone located in said pillow and having its mouth arranged toward the surface of the pillow to which the ear of the said person is applied, a crystal set located in said pillow and connected in circuit with said earphone, and extensible and contractible antenna and ground leads located in said pillow and connected in circuit with said crystal set and said earphone and accessible from the outside of said pillow for connection with an antenna and ground, means within the pillow for automatically returning said leads within the pillow when disconnected from said antenna and ground, and means for tuning the crystal set from outside of the pillow.
- 20 3. In a portable radio receiving apparatus,

in combination, a pillow for yieldingly supporting the head of a person, an earphone located in said pillow and having its mouth arranged toward the surface of the pillow to which the ear of the said person is applied, a casing within said pillow containing a crystal set and spring-actuated drums upon which are wound antenna and ground leads, means within the pillow for connecting the earphone and crystal set in circuit with said antenna and ground leads, and means for tuning the crystal set from outside the pillow, said antenna and ground leads being accessible from outside of the pillow to be unwound from said drums for connection with the antenna and ground.

In testimony whereof, I have signed my name to this specification.

JAMES H. NEAL.
